7 Claims. (Cl. 179—100.4)

1

This invention relates to devices which when actuated by power in an acoustic system, are capable of supplying power to an electrical system. The invention relates more especially to microphone and phonograph pickup devices and circuits, particularly where such devices are adapted to vary, by relatively direct means, the frequency or amplitude, or both, of the output signal of an associated electric wave generator. The invention is especially adapted for use with phonographs, radio-phonograph combinations, or with small portable radiophone systems and the like.

An important object of the invention is to provide a novel phonograph pickup adapted for use with amplitude modulation receivers either through the agency of a wireless link or by means of a direct connection.

Another object of the invention is to provide a phonograph pickup device capable of generating a frequency-modulated carrier wave adapted for F. M. (frequency modulation) reception by a standard A. M. (amplitude modulation) receiver.

A further object of the invention is to provide a phonograph pickup device capable of generating a frequency-modulated carrier wave adapted for reception by conventional F. M. receivers.

Still another object of the invention is to provide a novel phonograph pickup device having none of the disadvantageous characteristics of conventional crystal pickups, particularly with respect to use thereof under damp tropical conditions.

Another object of the invention is to provide a novel phonograph pickup device comprising a light-weight vibratory system together with a vacuum tube oscillator circuit for generating either an amplitude-modulated carrier wave, a frequency-modulated carrier wave, or both, or an audio frequency output signal corresponding in wave form to the acoustic energy being supplied to the device.

A further object of the invention is to provide a novel microphone and circuit therefor having the characteristics and advantages of the phonograph pickup hereinbefore enumerated.

The invention itself, as well as other objects thereof, may be clearly understood by reference to the accompanying drawings, wherein

Fig. 1 is a schematic circuit diagram of one embodiment of the invention;

Fig. 2 illustrates a fragmentary portion of a modification of the circuit of Fig. 1;

Fig. 3 illustrates a fragmentary portion of another modification of the circuit of Fig. 1;

Fig. 4 is a schematic circuit diagram of a further embodiment of the invention combined with a radio receiver of the superheterodyne type;

Fig. 5 is an explanatory diagram referred to in the description of the embodiment of Fig. 4;

Fig. 6 is a plan view of a phonograph pickup constructed in accordance with the principles of the invention;

Fig. 7 is a perspective view of a coil and a molded powdered iron core therefor employed in the pickup of Fig. 6;

Fig. 8 is a perspective view of the coil elements of Fig. 7 in operative relation with one form of vibrating armature;

Fig. 9 is a perspective view of a modified form of the armature of Fig. 8;

Fig. 10 is a plan view of an alternative form of pickup turned on its side and with the cover removed; and

Fig. 11 is a sectional view taken on the line 11—11 of Fig. 10.

Referring now to Fig. 1, there is illustrated one embodiment of the invention by means of which energy in an acoustic (or mechanical) system may be transformed into energy in an electrical system through the agency of a vacuum tube oscillator circuit. The embodiment illustrated includes an oscillator circuit of the tuned-grid tuned-plate type, although it will be understood that other types of oscillator circuits may be employed if desired. The particular oscillator chosen for purposes of illustration includes a tuned grid circuit including the grid inductance 1 and the grid tuning condenser 2. This tuned grid circuit is coupled to the grid electrode of the triode 3 by means of a coupling condenser 4. The anode circuit of the oscillator may comprise an inductance 5 tuned by a condenser 6. Plate-to-grid-circuit feedback occurs, as is well understood in the art, through the interelectrode capacity between grid and plate. A suitable grid leak 7 may be connected between the grid and cathode elements of the triode, as illustrated.

Where the device is to be employed in the production of phonograph records, an armature 8 and phonograph stylus-holding chuck 9 may be pivoted on the axis 10 in such a manner that vibrations transmitted to the stylus 11 by the phonograph record will cause the armature 8 to

oscillate in a similar manner relative to the inductance coil 1, as indicated by the double headed arrow. The armature 8 may comprise, for example, a single, short-circuited turn, as illustrated in detail in Fig. 10, or it may comprise a thin, relatively stiff leaf of metal foil as shown in Fig. 9. Whatever the specific form of the armature it is preferred that it be constructed of a light-weight non-magnetic metallic material, preferably aluminum or an aluminum alloy.

Where a short-circuited turn is employed, movement of the armature relative to the coil 1 results primarily in a change in the effective inductance of the coil, changing the resonant frequency of the grid circuit 1, 2, and causing the output of the oscillator to be frequency-modu-

iated in accordance with the audio frequency components derived from the recording.

Where the armature 8 comprises a thin leaf of metal foil, the relatively high resistance and large area of the leaf produces a condition wherein movement of the armature may have more effect upon the radio frequency resistance of the coil 1 than upon its inductance. Under these conditions vibration of the armature will produce corresponding changes in the Q (ratio of reactance to resistance) of the coil 1, and consequently in the magnitude of the radio frequency voltage thereacross. It follows that the output of the oscillator will be amplitude-modulated in accordance with the audio frequency components derived from the recording.

The modulated R. F. output of the oscillator may be received and detected in a conventional A. M. receiver 12, whether the pickup circuit is arranged to produce either an amplitude- or a frequency-modulated carrier wave. If the wave is amplitude-modulated the receiver 12 may be tuned to the receiver in the usual manner. If, on the other hand, the wave is frequency-modulated, reception may be obtained by slightly detuning the receiver so that a corresponding amplitude modulation is imparted to the received signal by the detuned high frequency circuits of the receiver. This hybrid signal, having both frequency and amplitude modulation, may then be detected in the usual manner.

If the armature 8 associated with the phonograph pickup is constructed to produce frequency modulation of the R. F. output of the oscillator, the radiated signal may be received by a conventional F. M. receiver 13. Where the frequency deviation produced by the vibrating armature is sufficient the signal may be radiated from the plate inductance 5 directly, or from an antenna attached thereto. However, if the receiver 13 is designed to operate on a signal of band width greater than that which can be supplied directly by the oscillator circuit alone, a suitable frequency multiplier 14 may be added to increase the deviation ratio of the signal. Means for accomplishing this are well known to those skilled in frequency modulation practices.

As described thus far the desired audio frequency signal has been secured by amplitude or frequency-modulating a carrier frequency with the desired signal, and by receiving and detecting this modulated carrier frequency in a suitable radio receiver. This mode of operation is, of course, particularly suitable where it is desired to operate a phonograph record player at some point remote from the receiver, and where it is desired to eliminate the necessity for a wire connection between the phonograph and the radio receiver. There is, however, another way in which the desired audio signal may be derived from the apparatus and supplied to suitable amplifying equipment. It has been found that where the vibrating armature 8 is of such construction as to produce substantial changes in the Q of the coil 1, there appears across the oscillator grid leak 7 a pulsating voltage, the audio frequency component of which is substantially directly proportional to the oscillations imparted to the stylus 11 by the phonograph record. Accordingly the audio signal present on the grid of the oscillator may be supplied directly to a suitable amplifier 15 and loudspeaker 16. By way of illustration, the coupling between the grid leak 7 and the amplifier 15 is shown to com-

prise a switch 17, an R. F. filter resistor 18, and an R. F. filter condenser 19.

The circuits hereinbefore described are not limited in their application to phonograph pickups alone. For example the circuit may advantageously be adapted to provide a microphone circuit having certain desirable characteristics. Thus the armature and stylus assembly 8-11 of Fig. 1 may be replaced by a diaphragm 20 as is illustrated in Fig. 2. This diaphragm may consist, for example, of a strip of 0.0003 duralumin ribbon such as is employed in the construction of ribbon microphones and the like. Under these conditions, the output of the oscillator may be largely amplitude modulated in accordance with the sound waves striking the ribbon, in a manner already explained.

A modification of the microphone circuit of Fig. 2 is shown in Fig. 3, wherein there is substituted for the duralumin ribbon 20, a diaphragm 21, e. g. of the type used in small loudspeakers, carrying at its apex a short-circuited turn 22 positioned adjacent the end of the oscillator grid coil 1. In this arrangement movement of the short-circuited turn 22 relative to the coil 1 tends to frequency-modulate the oscillator output in a manner already described with reference to Fig. 1.

Attention is now directed to the preferred embodiment of Fig. 4, in which the invention is shown in novel combination with a radio receiver of the superheterodyne type, and wherein a common oscillator circuit (associated with the triode elements of the detector-oscillator tube 23) is employed both as the local oscillator of the superheterodyne during radio reception, and as the modulated pickup oscillator during phonograph operation. The radio receiver itself may comprise a radio frequency amplifier 24, the detector-oscillator stage associated with the tube 23, an intermediate frequency amplifier 25, second detector and AVC stage 26, audio frequency amplifier 27, and the loudspeaker 28. An automatic volume control voltage may be fed back to the high frequency amplifier stages and the first detector by way of the conductor 29. When the switches 30 and 31 are in their left-hand position the ends of the oscillator tank coil 32 are connected, by way of the condensers 33 and 34, to the oscillator grid and oscillator anode respectively of the vacuum tube 23. In multi-band receivers the switches 30 and 31 are preferably a part of the receiver's band-changing switch. A predetermined intermediate tap point on the coil 32 may be connected to ground through a small adjustable trimmer condenser 35, as is well understood in the art. The oscillator tuning condenser 36 may be connected between the grid end of the coil 32 and ground, and may be ganged with tuning condenser 37 connected across the secondary of the R. F. transformer 38. A resistor 39 connected between oscillator grid and cathode serves as a grid leak, while the resistor 40, connected between oscillator anode and B+, serves as the usual R. F. filter in a shunt feed anode supply circuit. The intermediate frequency output of the tube 23 may be supplied to the I. F. amplifier 25 by way of a tuned transformer 41.

When it is desired to use the receiver for the reproduction of phonograph records, the switches 30 and 31 are moved to their right-hand position (shown), thereby disconnecting the oscillator tank coil 32 and its associated apparatus, and substituting therefor the phonograph pickup tank

coil 42, which corresponds to the coil 1 in Fig. 1. If desired this coil may be provided with a commutated iron core 43, as will be explained more fully in connection with the embodiment illustrated in Fig. 6. The coil 42 may be connected to the circuits within the receiver by way of a suitable phonograph pickup cable 44 connected to binding posts P, C, and G, indicating plate, chassis and grid connections respectively. The tank coil 42 may be tuned to resonate at a desired frequency by the addition of a small adjustable shunt tuning condenser 45. When employing the specific form of oscillator circuit shown in Fig. 4 it is generally preferred to design the coil 42 to have fewer turns in its grid-to-chassis portion than in its chassis-to-plate portion. By varying the relative number of turns in these portions the designer will be enabled to control the magnitude of the oscillator voltage which is applied to the pentode section of tube 23 by virtue of the internal connection of the third grid to the oscillator grid of the triode section of tube 23. In this regard still further latitude of design is allowed through the use of a separate oscillator (e. g. as shown in Fig. 1) in connection with a separate first detector or amplifier stage.

Where the moving system of the phonograph pickup is adapted largely to produce amplitude modulation of the oscillator output, the resonant tank circuit 42, 45, may be adjusted to resonate at the intermediate frequency of the receiver, which may, for example, be of the order of 455 kilocycles. However, if the moving system of the pickup is designed to produce largely a frequency-modulated oscillator output, the circuit 42, 45, is preferably tuned, in the absence of modulation, to resonate at a frequency slightly above or below the intermediate frequency, at a point on the I. F. selectivity characteristic where the said characteristic is substantially linear over an appreciable range of frequencies. This is the preferred adjustment.

To illustrate this mode of operation attention is directed to Fig. 5, which illustrates the overall intermediate frequency selectivity characteristic 46 of the I. F. portion of the receiver of Fig. 4. In the illustration the ratio of volts output e_0 to volts input e_1 is plotted against frequency. This characteristic may be more or less symmetrical about the intermediate frequency, which is here represented by the dashed line 47 and may be, for example, 455 kc. It will be observed that at some intermediate portion of the curve, say in the vicinity of the point 48, the characteristic is substantially linear over an appreciable range of frequencies. The point 48 may correspond, for example, to a frequency 5 kc. above the I. F., i. e. to a frequency of 460 kc. The linear portion of the characteristic may extend several kilocycles on either side of the point 48, as is indicated by the cross-hatched areas below the curve.

If now the frequency of the oscillator is made to vary about the frequency at 48 and out to limits represented by the solid lines 49 and 50, it will be seen that the radio frequency output e_0 of the I. F. amplifier will be caused to vary in amplitude between limits which are proportional to the vertical component of the distance between the intersections of the lines 49 and 50 with the characteristic 46. Similarly the output voltage of the second detector will be proportional to this same quantity, and consequently the operation of the device will be substantially linear and the quantity of reproduction satisfactory.

In practice it has been found convenient and desirable to tune the oscillator tank circuit to the point on the curve 46 (Fig. 5) where the slope is maximum, i. e., where the second derivative of the curve is zero. This may be done, for example, by adjusting the trimmer condenser 45 to give maximum audio output while playing a suitable single tone, constant amplitude, test recording.

If the magnitude of the modulated oscillator signal is sufficiently great, it has been found that the AVC voltage generated in the AVC section 26 of the receiver may be sufficiently high to bias the R. F. amplifier 24 to a point where radio signals are substantially blocked during phonograph operation, making it unnecessary to employ special switching devices for muting the input section of the receiver. Of course, with the local oscillator oscillating at or near the intermediate frequency, in general only those few signals differing from the oscillator frequency (or harmonics thereof) by an amount equal to the intermediate frequency could be transferred through the I. F. amplifier in any event.

In one physical embodiment of the above-described apparatus, in which the receiver's intermediate frequency was 455 kilocycles, the tuned circuit 42, 45, was adjusted to resonate at approximately 460 kilocycles and had an inductance of about 600 microhenries and a capacity of about 200 micromicrofarads. The inductance 42 had 200 turns and was tapped to give about 40 turns and 160 turns in the grid and plate sections of the coil respectively.

The system illustrated in Fig. 4 is of course particularly suitable where the receiver is of the type specifically adapted to receive frequency modulated signals and where the detector 26 is of the so-called discriminator variety. Under these conditions the tuned circuit in the pickup 45 may be adjusted to resonate normally at the center frequency of the intermediate frequency amplifier 25, whence the frequency modulated high frequency signal will be detected in the manner which is conventional for F. M. receivers. Reference is now made to a physical embodiment of the phonograph pickup, the principal structural features of which are illustrated in Figs. 6, 7, and 8. The pickup may comprise a "tone arm" 51, at one end of which means, such as the platform 52, are provided for supporting the stylus, the armature, and the various electrical circuit elements associated therewith. The assembly designated generally by reference character 53 provides a pivotal mounting for the stylus and armature. The tone arm structure generally and the mounting 53 are disclosed and claimed in a copending application of Elmer O. Thompson, Serial No. 357,322, filed September 18, 1940, now Patent No. 2,359,808, dated October 10, 1944. These elements are not in themselves a part of the present invention and hence are illustrated only as an example of the environment of the invention.

On the platform 52 there may be mounted an inductance element 54 which is secured to the platform by the clamping means 55. This inductance element may be of the form shown in greater detail in Figs. 7 and 8. In addition to the inductance element there may be provided a small adjustable tuning condenser 56 with which the element 54 may be tuned to resonance. The element 54 and the condenser 56 correspond respectively to the coil 42 and condenser 45 of Fig. 4. A terminal strip 57 having soldering lugs 58 may be provided to facilitate making the elec-

trical connections illustrated in Fig. 4. As illustrated in Figs. 7 and 8 the inductance element may comprise a comminuted iron core and shell 59 together with a suitable winding 60. The stylus, crank arm, shaft and armature structure and their relation to the inductance element 59, 60, are best shown in Fig. 8. The moving elements of the pickup comprise the shaft 61, the crank arm 62 and the stylus 63 which is riveted in the crank arm as described in the above-mentioned application of E. O. Thompson. The shaft 61 is resiliently held in the proper alignment by means of the armature clamp and bearing assembly 53. An upper rubber bearing element 64 and a lower rubber bearing element (not shown) provide the necessary resilience. The lower bearing element may be formed with a square cross section to fit the square bearing portion of the shaft 61, and to provide the necessary restoring force, as described in the above-mentioned Thompson application.

The apertured armature or vane 65 may consist of a modified channel member made from a thin sheet of a suitable light-weight metal. Aluminum foil having a thickness of 0.001 or 0.005 inch has been found satisfactory for this purpose. The vane should be firmly fixed to the shaft 61 so as to rotate or vibrate therewith. The apertured end of the vane 65, according to one form of the invention, is located near the inductance element 59, 60, and at a point where the alternating magnetic field about the element is fairly strong. The effect of the apertured vane in this field is similar to that of a single short-circuited turn of wire, and consequently the presence of the vane has an appreciable effect on the effective inductance of the coil 60. Moreover, as the vane is vibrated in a fashion to cyclically vary its distance from the said coil the inductance of the coil will, of course, vary cyclically in a similar manner. The operation of the device will be understood from the foregoing description.

An alternative form of the vane of Fig. 8 is illustrated in Fig. 9. The channel member 65 in this instance is not apertured and hence presents a flat unbroken surface to the associated inductance element. With this form of vane, the chief effect produced on the coil 60 by the presence and vibration of the vane is a corresponding variation in the effective resistance of the coil. This effect is largely produced by the eddy currents set up in the vane by the action of the alternating magnetic field surrounding the coil. As explained in connection with the schematic diagram of Fig. 1, either the inductance variation method or the resistance variation method may be used. It should be understood, however, that in general it will not be possible readily to secure pure inductance variation without some resistance variation, or vice versa.

In order to increase the magnetic flux in the immediate vicinity of the vibrating vane, it has sometimes been found convenient to associate with the coil 60 a comminuted iron core and shell member 59, as illustrated in Fig. 7. The effect of such a member is to confine the greater part of the flux to a more or less concentrated path, in which the vibrating vane may be situated, thus greatly increasing the effectiveness of the relatively weak vibrations imparted to the vibrating system by the undulations cut in the phonograph record.

With reference to the preferred embodiment illustrated in Fig. 4, it should be understood that

variations in the constants of the resonant circuit 42, 45 may be secured by varying the capacity of the condenser 45 just as readily as by varying the inductance or effective resistance of the coil 42. Thus the movable plate of the condenser 45 (indicated by the curved arrow) might be mechanically coupled to the phonograph stylus to enable the vibratile plate of the condenser to vibrate in accordance with the motion of the stylus. By way of example, the vibrating system of Fig. 9 might be employed without change, the channel member 65 cooperating with the stationary plate of condenser 45, Fig. 4, to provide a condenser whose capacity is varied in substantial accordance with the motion of the stylus 63. Thus, the pickup of Fig. 6 utilizing the vane 65 of Fig. 9, could be employed with slight modification to vary the capacitance. It would merely be necessary to affix a stationary condenser plate in the position of element 54, moving the latter to another position, omit condenser 56, and make the necessary electrical connections.

An alternative physical embodiment of a pickup adapted for use with this invention is illustrated in Figs. 10 and 11. The pickup head may comprise, for example, a molded case 66 and cover 67. The case 66 may be provided with a suitable recess 67a to receive a tuning condenser 68, whose function corresponds to that of the condenser 45 in Fig. 4. A cross-shaped recess 69 having a generally semi-circular cross-section may also be provided to receive the vibrating elements of the pick-up. The cover member 67 may be provided with similar and opposing recesses.

The vibrating member 70 may comprise a single aluminum casting having at its upper end a single short-circuited turn or ring 71, at its lower end a needle chuck to receive the needle or stylus 72, at its right-hand end a first pivot having a resilient rubber bearing member 73, and at its left-hand end a second pivot provided with a threaded passage to receive the cooperating needle holding screw 75. This pivot is also provided with a rubber bearing member 74. A projecting tip on the upper end of the shorted turn 71 may be imbedded in a piece of resilient material, such as rubber, to provide mechanical damping and to permit accurate centering of the armature.

Positioned in a circular recess in the case 66 and in line with the short-circuited turn 71 there may be provided a suitable coil 77 corresponding generally to the coil 42 of Fig. 4, or the coil 1 of Fig. 1. An iron core may be provided if desired to increase the effectiveness of small movements of the short-circuited turn 71 relative thereto as explained hereinbefore.

The vibrating vanes 64 and 65 illustrated in Figs. 8 and 9 have an important advantage over the vibrating member 70 of Fig. 10. Because of the relatively large surface which these vanes present to the air there is derived an appreciable degree of air damping which acts to damp out undesired mechanical resonances which otherwise would have to be suppressed by other means. Of course if it is desired additional damping may be applied by any of the known methods, e. g. by the means described in the above mentioned application of E. O. Thompson.

Although the invention has been illustrated and described with reference to certain preferred embodiments, it will be understood that further alterations and modifications thereof may be made within the scope of this invention as defined in the appended claims.

I claim:

1. In an electro-acoustic transducer: an oscillation generator comprising a resonant frequency-determining circuit, a vacuum tube, and a grid leak connected in the grid circuit of said tube, said generator being adjusted to produce oscillations of high frequency; a vibratile electrically-conductive, loss-inducing element positioned in a portion of the alternating magnetic field of said resonant circuit and adapted to be vibrated at a low frequency, vibration of said element effecting corresponding variations in the resistance of said resonant circuit, thereby to amplitude modulate the generated high frequency oscillations and to develop a corresponding low frequency signal across said grid leak; and a low frequency output circuit coupled to said grid leak for utilizing the low frequency signal developed thereacross.

2. A phonograph record reproducer comprising: an oscillator having a resonant circuit, a vacuum tube, and a grid leak resistance connected in the grid circuit of said tube, said resonant circuit including an inductance coil and a capacitance, said oscillator being adjusted to oscillate at a radio frequency; a record-engaging stylus; a vibratile metallic vane mechanically coupled to said stylus and electromagnetically coupled to said inductance coil, vibration of said vane by said stylus at an audio frequency rate effecting corresponding variations in the Q of said coil, thereby to amplitude-modulate the radio frequency oscillation generated by said oscillator, and to develop a corresponding audio frequency signal voltage across said grid leak resistance; means responsive to the audio frequency signal voltage across said grid leak resistance for deriving said signal voltage therefrom; and means for utilizing said derived signal voltage.

3. A phonograph record reproducer comprising: an oscillator having a resonant circuit, a vacuum tube, and a grid leak resistance connected in the grid circuit of said tube, said resonant circuit including an inductance coil and a capacitance, said oscillator being adjusted to oscillate at a radio frequency; a record-engaging stylus; a vibratile metallic vane mechanically coupled to said stylus and electromagnetically coupled to said inductance coil, vibration of said vane by said stylus at an audio frequency rate effecting corresponding variations in the Q of said coil, thereby to amplitude-modulate the radio frequency oscillation generated by said oscillator, and to develop a corresponding audio frequency signal voltage across said grid leak resistance; and means for utilizing said audio frequency voltage.

4. A phonograph record reproducer comprising: an oscillator having a resonant frequency-determining circuit and a vacuum tube, said resonant circuit including an inductance coil and a capacitance, said oscillator being adjusted to oscillate at a radio frequency; a record-engaging stylus; a vibratile metallic vane mechanically coupled to said stylus and electromagnetically coupled to said inductance coil, vibration of said vane by said stylus at an audio frequency rate effecting corresponding variations in the Q of said coil, thereby to amplitude modulate the radio frequency oscillations generated by said oscillator; and a low-frequency load impedance included in a circuit of said oscillator tube for deriving an audio frequency signal voltage directly from said tube, said voltage corresponding to the

amplitude modulation of said radio frequency oscillation.

5. A phonograph record reproducer comprising: an oscillator including a resonant circuit, a vacuum tube, and a grid leak resistance connected in the grid circuit of said tube, said oscillator being adjusted to oscillate at a radio frequency; a record-engaging stylus; means including a vibratile, electrically-conductive, loss-inducing element mechanically coupled to said stylus and electrically associated with said resonant circuit for amplitude-modulating the radio frequency oscillation generated by said oscillator in accordance with audio frequency vibrations of said stylus, and to develop a corresponding audio frequency signal voltage across said grid leak resistance; and means responsive to the voltage across said grid leak resistance for deriving the audio frequency signal voltage therefrom.

10 20 25 30

6. A phonograph record reproducer comprising: an oscillator including a resonant circuit, a vacuum tube, and a grid leak resistance connected in the grid circuit of said tube, said oscillator being adjusted to oscillate at a radio frequency; record-engaging stylus; means operable by said stylus for amplitude-modulating the radio frequency oscillation generated by said oscillator in accordance with recorded audio frequency vibrations, and to develop a corresponding audio frequency signal voltage across said grid leak resistance; and means responsive to the voltage across said grid leak resistance for deriving the audio frequency signal voltage therefrom.

7. A phonograph record reproducer comprising: an oscillator having a resonant frequency-determining circuit and a vacuum tube, said oscillator being adjusted to oscillate at a radio frequency; apparatus including an impedance-varying phonograph pickup operatively associated with said oscillator for amplitude-modulating—in accordance with recorded audio frequency vibrations—the radio frequency oscillation generated by said oscillator; a resistor included in a circuit of said oscillator tube; and means for deriving an audio frequency signal voltage directly from said resistor, said voltage corresponding to the amplitude modulation of said radio frequency oscillation.
